UNITED STATES PATENT OFFICE.

JOSEPH JAUCH, OF MERIDEN, CONNECTICUT, ASSIGNOR TO THE BRADLEY & HUBBARD MANUFACTURING COMPANY, OF SAME PLACE.

AIR-DISTRIBUTER FOR ARGAND LAMPS.

SPECIFICATION forming part of Letters Patent No. 409,466, dated August 20, 1889.

Application filed April 8, 1889. Serial No. 306,336. (No model.)

To all whom it may concern:

Be it known that I, JOSEPH JAUCH, of Meriden, in the county of New Haven and State of Connecticut, have invented a new 5 Improvement in Air-Distributors for Argand Burners; and I do hereby declare the following, when taken in connection with accompanying drawings and the letters of reference marked thereon, to be a full, clear, and exact description of the same, and which said drawings constitute part of this specification, and represent, in—

Figure 1, a side view of a distributor detached; Fig. 2, a top view of the same; Fig. 15 3, a vertical section of a wick-tube, showing side view of the distributor as arranged therein; Fig. 4, a vertical section of the distributor enlarged; Fig. 5, a vertical section of a plain distributor of equal height of the distributor, Fig. 4, illustrating the advantages of the invention; Fig. 6, a vertical section of a wick-tube and distributor to take the entire internal supply of air; Figs. 7, 8, and 9, vertical sections of the distributor, illustrating modifications in its construction.

This invention relates to an improvement in air-distributors employed to direct the internal current of air onto the flame of "Argand burners." These distributors are introduced within the inner tube of the burner, and so as to receive the whole or a portion of the internal current, the upper end of the distributor above the base of the flame perforated, so that the air will flow outward 35 through the perforations into the flame, the object of the distributor being to equally distribute the air around the flame and prevent irregular currents. These distributors are of various forms, sometimes in shape of a thimble set within the central tube, but so that the closed end projects above the upper end of the central tube, the side wall of the thimble perforated. In this case the entire supply of air for the interior of the flame passes through 40 the distributor. In other cases the distributor is placed upon the upper end of a tube arranged concentrically within the burner, but of smaller diameter than the internal diameter of the burner, the distributor perforated, so that air received through its tube

will be injected onto the flame. In this case but a portion of the internal air comes through the distributor, the remainder of it passing up outside the distributor into the flame. These distributors, while more generally employed in lamps, are equally adapted to gas-burners. The advantages of such a distributor is the direction into the flame of air to produce so perfect combustion that the flame will be as near white as possible—the more 60 air the better the combustion and the whiter the flame. To produce a perfect burner, the air should be injected near the base of the flame and in sufficient quantity to produce the desired combustion. 65

The object of my invention is to accomplish this desirable result; and it consists in constructing the exposed surface of the distributor with alternating series of substantially vertical and horizontal perforations, so 70 that the air coming into the distributor will be ejected in alternately horizontal and vertical jets, the combined action of the jets being to deflect the air laterally into the flame.

I represents the invention as applied to an Argand burner for lamps and employing a wick. 75

A represents the inner tube, and B the outer tube, between which the wick C is arranged in the usual manner. 80

In the preferred construction the distributor-tube D is of smaller diameter than the internal diameter of the central tube or burner, and onto this tube D the distributor E is set. The distributor expands from the inner tube 85 into the required diameter above the burner, so as to form substantially a button F over the burner, and against which the flame will strike and be deflected outward. The top or upper portion of the distributor is constructed with a 90 series of annular offsets, forming horizontal surfaces a, alternating with vertical surfaces b, as seen in Fig. 4. These surfaces form the walls of the distributor. This distributor is made from sheet metal and readily struck or spun into the required shape. The horizontal surfaces are pierced with numerous holes d, and the vertical surfaces are pierced with similar holes e. The holes d open vertically upward and the holes e open hori- 95 100

zontally toward the flame. The air passes into the distributer under the natural flow induced by the heat, and is ejected outward through the vertical and the horizontal perforations. The vertical jets of air meet the horizontal jets immediately on their escape through the perforations, and because of such meeting of the currents of air the air is deflected and thrown outward in a slightly inclined direction, as indicated by the arrows in Fig. 4, and thus pass directly to the flame. The extent of the offsets—that is, the height and the width of the surfaces—is only substantially that necessary for the perforations and to leave metal to give requisite strength, so that the height of the perforated or offset portion of the distributer is only that which is necessary to make the number of perforations represented by the said offsets; or, in other words, if the surface of the distributer were vertical, as indicated in Fig. 5, and of the same height as the distributer, there would be only as many series of perforations as there are offsets in the improved distributer, but because of the offsets the horizontal surfaces are presented, and these being perforated correspondingly increase the amount of perforated surface, and consequently the amount of air which will be thrown into the flame—that is to say, double the amount of perforations is produced by these offsets over what there would be in the same height of a plain surface. The result of this construction of distributer is that a greatly-increased amount of air for the same extent of space is brought to the flame, and because of the reducing of the space for the increased quantity of air the perforated space may stand so near the base of the flame that the injection of the air into the flame will be substantially at the base.

The distributer may be perforated upon its under side, as represented in Fig. 3, for the escape of a portion of the air radially outward into the flame below the offset portion; but this is not material to the present invention. Under this construction all the air may be taken through the tube which leads into the distributer, or, as in some cases, a portion of the air may pass up outside the distributer, as indicated by the arrows, Fig. 3.

In that class of distributers in which the

body of the distributer corresponds substantially in diameter to the internal diameter of the burner or wick-tube the upper end of the distributer is offset in the same manner as I have described and as seen in Fig. 6, accomplishing the same result of substantially doubling the quantity of air introduced into the flame within a given height.

In some cases it may be desirable to make the offsets both above and below the largest diameter of the distributer, as seen in Fig. 7, or it may be desirable to make the offsets entirely below, as in Fig. 8. I therefore do not wish to be understood as limiting the invention to any particular arrangement of the perforated offsets.

Instead of making the alternating series of horizontal and vertical perforations by constructing the distributer with offsets, a similar result may be attained by making the wall of the distributer plain and inclined, as seen in Fig. 9, and producing the series of perforations alternately vertical and horizontal, as seen in that figure, whereby vertical and horizontal currents of air will be mingled and deflected into the flame.

The illustrations which I have thus made of the invention will be sufficient to enable others skilled in the art to apply the invention to other constructions of distributers, and to gas-burners as well as to lamps.

I claim—

1. An air-distributer for Argand burners, adapted to be concentrically arranged in the burner and having an exposed surface above the burner, the said exposed surface perforated with alternating series of vertical and horizontal perforations, substantially as described.

2. The herein-described distributer for Argand burners, constructed with one or more annular offsets forming substantially alternating horizontal and vertical surfaces, the said horizontal and vertical surfaces perforated to form alternating series of vertical and horizontal perforations, substantially as described.

JOSEPH JAUCH.
